The ornamental design for a combination parking structure and train station, as shown and described.

DESCRIPTION

FIG. 1 is a perspective view of a combination parking structure and train station showing my design;

FIG. 2 is a plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a perspective view thereof, shown without environmental subject matter.

The broken line showing of the roadway and ramps in FIGS. 1-6 is for illustrative purposes only and forms no part of the claimed design.

A bottom view of the combination parking structure and train station is flat and unornamental.
